UNITED STATES PATENT OFFICE.

HARRY C. O'BLENESS AND ERWIN C. MERWIN, OF ATHENS, OHIO.

APPARATUS FOR ELEVATING LIQUIDS.

No. 814,072.

Specification of Letters Patent.

Patented March 6, 1906.

Application filed May 17, 1905. Serial No. 260,796.

To all whom it may concern:

Be it known that we, HARRY C. O'BLENESS and ERWIN C. MERWIN, citizens of the United States, residing at Athens, in the county of 5 Athens and State of Ohio, have invented certain new and useful Improvements in Apparatus for Elevating Liquids, of which the following is a specification.

This invention relates to that type of apparatus designed particularly for elevating liquids in wells or pools or the like and utilizing compressed air or a similar fluid for forcing the liquid upwardly to a suitable point of discharge.

15 The invention resides in novel details of construction affording a mechanism of simplified nature and one in which the parts are automatically operated entirely with resultant advantages of obvious import.

20 The invention includes the use of a compressor, of a compressed-air reservoir, suitable liquid-reservoirs adapted to alternately receive the liquid which is discharged therefrom under pressure of the compressed air led 25 from the compressed-air reservoir, and special means whereby the compressed air used for discharging the liquid from the liquid-reservoirs is again admitted to the compressor for recompression.

30 The invention also embodies peculiar valve mechanism which will appear more fully as the description proceeds.

For a full description of the invention and the merits thereof and also to acquire a knowledge 35 of the details of construction of the means for effecting the result reference is to be had to the following description and accompanying drawings, in which—

Figure 1 is a view, partially in section and 40 partially in elevation, of an apparatus embodying the invention, one of the liquid-reservoirs having the liquid discharge therefrom, the main valve being open to the filled liquid-reservoir preparatory to discharge of 45 the liquid therefrom under the pressure of the compressed air. Fig. 2 is a view similar to Fig. 1, the position of the main valve being reversed, one of the puppet-valves being shown open in dotted lines and the auxiliary 50 valve connected therewith having been actuated to a position establishing communication between the pressure-chamber and the compressed-air reservoir.

Corresponding and like parts are referred 55 to in the following description and indicated

in both the views of the drawings by the same reference characters.

Specifically describing the structure illustrated in the drawings, the numerals 1 and 2 designate a pair of liquid-reservoirs, which 6c will be described as "water-reservoirs" for the purposes of this description, but which are of course adapted to receive any suitable liquid. The water-reservoirs 1 and 2 are in communication with a liquid-supply, in this 65 instance having valved connection, the valves (indicated at 3) with a supply-pipe 4 directly connected with a strainer 5. Any suitable inlet may be provided for the reservoirs 1 and 2, however. Air-pipes 6 and 7 connect 70 with the reservoirs 1 and 2, respectively, at one end, the opposite ends of the air-pipes being connected with a valve-chamber 8, in which operates the valve 9, composed of the heads 9^a and 9^b, having piston fit in the chamber 8.

The compressed-air reservoir is indicated at 10 and is connected by a pipe 11 with the valve-chamber 8. The reservoir 10 is supplied by a compressor 12 of any suitable 80 type, a pipe 13 connecting the compressor with the reservoir. The compressor is also connected with the valve-chamber 8 by means of a suction-pipe 14, the latter communicating or directly leading to an air-passage 85 15, preferably located at the upper portion of the chamber 8, said air-passage 15 communicating at its ends, as shown at 16, with the interior of the valve-chamber.

A suitable discharge-pipe 17, having 90 branches 18 leading directly into the reservoirs 1 and 2, leads off to a suitable point of discharge for the liquid or water, and check-valves 19 are disposed in the length of the branch pipes 18 to prevent the water or liquid 95 from flowing back into the reservoirs 1 and 2 after being forced into the pipe 17.

A pressure-chamber 20 is used in connection with the valve-chamber 8 and may be supported by any suitable means adjacent 100 said chamber 8. Operating in the pressure-chamber 20 is a piston 21, having a piston-rod 22 suitably connected with the valve 9, so as to actuate said valve as the piston is moved. The piston 21 is operated by pressure alternately at opposite sides thereof, and for this purpose the pressure-chamber 20 is supplied with a pressure medium at opposite ends (indicated at *x* and *w*) by means of pipes 23 and 24. The pipe 23 is connected 105 to the pressure-chamber 20 at the side 110 indicated at *x*, and the pipe 24 is connected to the pressure-chamber 20 at the side indicated at *w*.

with a slide-valve chamber 25^a, in which operates an auxiliary slide-valve 25, the chamber 25^a being connected by a short pipe B to another pipe A, directly connected with the pipe 11. The valve 25 is adapted to move so that compressed air may pass from the pipe A through the pipe B and thence through the chamber 25^a to the pipe 23 into the pressure-chamber 20. The pipe 24 connects with a second valve-chamber 26^a, in which operates a second auxiliary slide-valve 26, and this valve governs the admission of compressed air to the chamber 20 through the said pipe 24. The pipe A connects with the chamber 26^a, and passage of the compressed air from the pipe A through the pipe 24 is governed by the valve 26 aforesaid. The pipe 24 connects with the end w of the chamber 20. The auxiliary slide-valves 25 and 26 are adapted to operate so as to permit the pipes 23 and 24 to be open to the exterior atmosphere at 27 and 28, each of the valve-chambers 25^a and 26^a having an open end, preferably, for the above purpose, through which the air or fluid 25 actuating piston 21 when exhausted from the pressure-chamber 26 passes.

Located in the length of the air-pipes 6 and 7 are valve-compartments 29 and 30, respectively, the same communicating with the pipes with which they are connected and provided with openings normally closed by means of puppet-valves 31 and 32, respectively. Springs 33 are preferably utilized to keep the puppet-valves 31 and 32 adjusted, although 35 levers and weights may be used to accomplish the same purpose, and the stems 34 of said valves 31 and 32 are operably connected in any suitable manner to accomplish the desired results with the auxiliary slide-valves 25 and 26. The stem 34 of the valve 31 connects with the valve 25, whereas the valve 32 is similarly connected with the valve 26.

It will be understood that the pipe A need not necessarily be connected directly with the pipe 11, as shown in the drawings; but it may be connected with the chamber 8 at a point which will always be intermediate the heads 9^a and 9^b. The above is a more simple construction and answers the same purpose with regard to the supply of compressed air to the pipes 23 and 24.

A description of the operation of the invention will bring out the advantages of the structure set forth. When the parts of the apparatus are in the positions illustrated in Fig. 1, the main valve 9 is so disposed with regard to the location of the valve-heads 9^a and 9^b that the compressed air from the reservoir 10 is passing into the valve-chamber 8 55 through the pipe 11 and through said valve-chamber 8 between the heads 9^a and 9^b into the air-pipe 7 to the water-reservoir 2. The water-reservoir 2 is filled with water, and this water is being expelled or discharged therefrom by the compressed air, which forces the

water through the branch pipe 18 and out through the discharge-pipe 17, the inlet-valve 3 of the reservoir 2 being closed. The compressor in this operation is at the same time exhausting the air from the reservoir 1, 70 said air having been previously forced into said reservoir to discharge its contents, the suction of the compressor created through the suction-pipe 14, which communicates with the chamber 8, tending to create a 75 vacuum in the reservoir 1, the air-passage 15 being open to the pipe 6 at one end, as shown clearly in Fig. 1. The tendency to create a vacuum, due to the action of the compressor 12, in the reservoir 1 and the pipe 6 will effect 80 automatic opening of the puppet-valve 31 at a predetermined time, and in so opening the connection between said valve 31 and the auxiliary slide-valve 25 is such that the slide-valve 25 is moved to connect the pipe 23 with 85 the pipe B which leads from the pipe A, permitting the compressed air to pass from the pipe 11 to pipe A, pipe B, between the heads of the valve 25, and thence through the pipe 23 into the end x of the chamber 20, where it will 90 bear against the side of the piston 21, forcing the said piston toward the opposite end of the chamber 20, reversing the position of the valve 9. When the puppet-valve 31 is opened, free air is of course drawn into the 95 pipe 6, and as soon as the suction in the pipe 6 is relieved the valve 31 automatically closes, cutting the pipe 23 out of communication with the pipe B by moving the valve 25. When the valve 9 is reversed, the head 9^b of 100 said valve will cut off communication between the portion of the chamber 8 receiving the compressed air from the pipe 11 and the air-pipe 7, and the compressed air will now 105 pass into the chamber 8 and from said chamber into the pipe 6 and then into the reservoir 1, which latter has been previously filled with water by the suction-strokes of the compressor, and the operation of the valve devices 26 and 32 is similar to that described 110 before with relation to the valves 31 and 25. When the valve 32 opens, the slide-valve 26 is moved to connect the pipe 24 with pipe A and compressed air passes through the pipe A into the chamber 26^a and through the pipe 24 into the end w of the pressure-chamber 20. It will of course be understood that 115 when the chamber 20 is receiving compressed air through the pipe 23 the pipe 24 is open at 28, permitting the air upon the opposite side of the piston 21 to exhaust at 28, and when the chamber 20 receives the air through the pipe 24 the pipe 23 is open at 27 to permit exhausting of air through this pipe in the movement of the piston 21.

When the apparatus as hereinbefore described is used primarily as a water-elevator, there is comparatively little air lost, and such loss is compensated for by the air which is admitted upon opening of the valves 31 and 32 130

in the operation which has been before described. When, however, it is desired to use other pneumatic tools or operate other machinery by the same compressor 12, a pressure-regulated device is utilized for admitting air directly to the compressor, this being necessary, due to the fact that in the use of other tools operated by the said compressor 12 an increased amount of compressed air is permitted to escape to the atmosphere after it has done its work and the pressure in the reservoir would be decreased to a point below the minimum necessary for operation of the devices with no free air supplied to the compressor. It is thus designed to provide an air-inlet pipe 35 directly connected with the suction-pipe 14 adjacent the point of juncture of said pipe 14 with the compressor, and free air is adapted to be admitted into the pipe 35 according to the operation of a pressure-regulator, which is adapted to actuate a cut-off valve 36, which normally closes the pipe 35. The pressure-regulator preferably utilized includes a cylinder 37, in which moves a piston 38, said piston being connected by a rod 39 with a lever 40, pivoted at 41 to a suitable casing 42 for the valve 36. The lever 40 is provided with a balance-weight 43, and the cylinder 37 has a pipe 44 connecting the same with the reservoir 10. When the pressure in the reservoir 10 is at the normal maximum, the valve 36 is closed, said pressure coacting with the piston 38 to hold the lever 40 in such a position that said valve prevents entrance of air into the pipe 35. On decrease of the pressure in the reservoir 10 the piston 38 is relieved to a certain extent and moves upwardly under actuation of the weight 43, and the lever 40, pulling downwardly upon the valve 36, will open the same and air will be drawn into the compressor through the pipe 35 to an extent sufficient to increase the pressure in the reservoir 10 to a maximum in a manner which will be apparent. It will be noted that a diaphragm or similar pressure-operated device may be substituted for the pistons 38 and 21 within the contemplation of the invention and accomplish the same desirable results.

Having thus described the invention, what is claimed as new is—

1. In an apparatus of the type described, the combination of a pair of water-reservoirs, a discharge for said reservoirs, a valve-chamber, air-pipes connecting the valve-chamber and water-reservoirs, a main valve operating in said valve-chamber and governing the supply of air to the air-pipes aforesaid, a compressed-air reservoir connected with the valve-chamber, a compressor, a suction-pipe connecting the compressor and valve-chamber, a pressure-actuated device connected with the main valve, independent valved connections with the compressed-air reservoir arranged to supply pressure at opposite

sides of the pressure-actuated device, the valves of the mentioned connections being operable by suction of the compressor.

2. In an apparatus of the type described, the combination of a pair of water-reservoirs, a discharge for said reservoirs, a valve-chamber, air-pipes connecting the valve-chamber and water-reservoirs, a main valve operating in said valve-chamber and governing the supply of air to the air-pipes aforesaid, a compressed-air reservoir connected with the valve-chamber, a compressor, a suction-pipe connecting the compressor and valve-chamber, a pressure-actuated device connected with the main valve, independent valved connections with the compressed-air reservoir arranged to supply pressure at opposite sides of the pressure-actuated device the valves in the length of the last-mentioned connections being operated by suction of the compressor created in the length of the air-pipes.

3. In an apparatus of the class described, the combination of a pair of water-reservoirs, a discharge for said reservoirs, a valve-chamber, a main valve operating in said chamber, air-pipes connecting the valve-chamber and the water-reservoirs, a compressed-air reservoir connected with the valve-chamber, a compressor, a suction-pipe connecting the compressor and the valve-chamber, whereby air forced into the water-reservoirs to discharge water therefrom, may be returned to the compressor, means for actuating the main valve aforesaid, air-inlets in the length of the air-pipes aforesaid between the points of connection of the same with the water-reservoirs and the valve-chamber, and valves for said inlets operable by suction of the compressor.

4. In an apparatus of the class described, the combination of a pair of water-reservoirs, a discharge for said reservoirs, a valve-chamber, a main valve operating in said chamber, air-pipes connecting the valve-chamber and the water-reservoirs, a compressed-air reservoir connected with the valve-chamber, a compressor, a suction-pipe connecting the compressor and the valve-chamber, whereby air forced into the water-reservoirs to discharge water therefrom, may be returned to the compressor, means for actuating the main valve aforesaid, air-inlets for supplying air to the compressor, valves for said air-inlets operable by action of the compressor, and a pressure-operated device for actuating the main valve and controlled by the valves of the air-inlets aforesaid.

5. In an apparatus of the class described, the combination of a pair of water-reservoirs, a discharge for said reservoirs, a valve-chamber, a main valve operating in said chamber, air-pipes connecting the valve-chamber and the water-reservoirs, a compressed-air reservoir connected with the valve-chamber, a compressor, a suction-pipe connecting the

compressor and the valve-chamber, whereby air forced into the water-reservoirs to discharge water therefrom, may be returned to the compressor, means for actuating the main valve aforesaid, air-inlets in the length of the air-pipes between the points of connection thereof with the water-reservoirs and the valve-chamber, puppet-valves for said air-inlets operable by suction of the compressor,

10 a pressure-chamber, a piston arranged in said chamber and connected with the main valve, pipes connecting the compressed-air reservoir with the pressure-chamber to supply pressure at opposite sides of the piston, and auxiliary valves connected with the puppet-valves and governing the supply of the compressed air from the compressed-air reservoir to the pressure-chamber through the connecting-pipes.

6. In an apparatus of the class described, 20 the combination of a pair of water-reservoirs, a discharge for said reservoirs, a valve-chamber, a main valve operating in said chamber, air-pipes connecting the valve-chamber and the water-reservoirs, a compressed-air reservoir connected with the valve-chamber, a compressor, a suction - pipe connecting the compressor and the valve-chamber, whereby air forced into the water-reservoirs to discharge water therefrom may be returned to 25 the compressor, means for actuating the main valve aforesaid, and an air-inlet for the compressor controlled by the pressure in the compressed-air reservoir.

7. In an apparatus of the class described, 30 the combination of a pair of water-reservoirs, a discharge for said reservoirs, a valve-chamber, a main valve operating in said chamber, air-pipes connecting the valve-chamber and

the water-reservoirs, a compressed-air reservoir connected with the valve-chamber, a 40 compressor, a suction - pipe connecting the compressor and the valve-chamber, whereby air forced into the water-reservoirs to discharge water therefrom may be returned to the compressor, means for actuating the main 45 valve aforesaid, an air - inlet for the compressor, and a valve governing said air-inlet of the compressor and controlled by variation in pressure in the compressed-air reservoir.

8. In an apparatus of the class described, 50 the combination of a pair of water-reservoirs, a compressed-air reservoir arranged to supply air to the water-reservoirs, valve means governing the supply of air from the compressed-air reservoir to the water-reservoirs, a compressor, and an air-inlet for the compressor controlled by variation of pressure in the compressed-air reservoir.

9. In an apparatus of the class described, 60 the combination of a pair of water-reservoirs, a compressed-air reservoir arranged to supply air to the water-reservoirs, valve means governing the supply of air from the compressed-air reservoir to the water-reservoirs, a compressor, an inlet for supplying air directly to 65 the compressor, a valve governing said inlet, and a pressure-controller connected with the compressed-air reservoir and the valve of the air-inlet aforesaid.
